UNITED STATES PATENT OFFICE.

SPENCER C. CARY, OF BROOKLYN, AND JAMES M. BETTON, OF MOUNT VERNON, NEW YORK, ASSIGNORS, BY DIRECT AND MESNE ASSIGNMENTS, TO CARY MANUFACTURING COMPANY, OF BROOKLYN, NEW YORK, A CORPORATION OF NEW YORK.

MEANS FOR CLEANING METALS PREPARATORY TO WELDING.

1,419,717.

Specification of Letters Patent. Patented June 13, 1922.

Application filed February 8, 1917. Serial No. 147,350.

To all whom it may concern:

Be it known that we, SPENCER C. CARY and JAMES M. BETTON, both citizens of the United States, residing at the city of New

5 York, borough of Brooklyn, county of Kings, and State of New York, and Mount Vernon, Westchester County, State of New York, respectively, have invented a certain new and useful Means for Cleaning Metals 10 Preparatory to Welding, of which the following is a specification.

This invention is an apparatus for removing the scale or oxidation from sheet metal, the same being useful, more particularly, in 15 connection with a process of welding by electric heat and pressure as disclosed in an application filed by one of the parties hereto, Spencer C. Cary, Serial No. 89289, although it is manifest that the apparatus of the present invention may be used for other purposes.

The object of the invention is to effect the removal of the scale or oxidation from the 20 marginal portions of sheet metal in a thorough manner, to the end that the operation upon said marginal portions of the metal may be carried on expeditiously and economically, whereby the subsequent step of welding is accomplished efficiently owing to 25 the fact that the resistance to the flow of the welding current offered by the cleaned marginal portions of the metal is uniform throughout the length of the resulting seam weld between the contiguous edges of two 30 pieces of sheet metal.

Further, the invention has in view to enable the sheet metal to be introduced into the apparatus for a definite predetermined distance; to provide for the control of the apparatus at will of an attendant, and to secure 35 precision and efficiency in the cleaning operation upon the metal.

Stated in general terms, the invention comprises a chamber, means for locating the 40 work in the form of sheet metal in a definite position within the chamber, and means for directing a sand blast into contact with the work, whereby the attrition of the sand blast upon the surface of the work removes 45 in an efficient manner the surface oxidation or scale notwithstanding the existence of any irregularity in the surface of the metal.

The invention embodies, also, suitable means for effecting a relative movement be-

tween the work or metal and the sand blast, 55 to the end that the field of said sand blast is restricted to a definite marginal portion of the work or metal.

The invention embodies, also, the use of a plurality of nozzles positioned for directing 60 sand blasts into contact with the respective surfaces of the sheet metal, combined with means for effecting a relative movement between the work and said nozzles.

The invention embodies, also, the provision 65 of means for supporting one or more nozzles in position for movement along a definite path with respect to the marginal portion of the work.

The invention embodies, also, the employment of means for imparting movement simultaneously to a plurality of sand blast nozzles so as to obtain the action of the sand blasts against the respective surfaces of the sheet and along definite paths for the removal 75 of scale from the marginal portions of said sheet.

Further, the invention consists in the provision of means for controlling at will the flow of air through the apparatus; further, 80 in means for excluding the escape of the sand from the apparatus to the end that the work of the operator shall not be interfered with to an appreciable extent by the escaping air and sand; and, further, in means for 85 imparting automatically to the plurality of nozzles a to-and-fro traversing movement with respect to the work-positioning means.

Other features and advantages of the invention will appear from the following description taken in connection with the drawings, wherein—

Figure 1 is a vertical section through an apparatus embodying this invention.

Figure 2 is another vertical section in a 95 direction substantially at right angles to Figure 1, with the operating chamber partly broken away, and illustrating the position of the work within the chamber as determined by the work-locating devices. 100

Figure 3 is a sectional plan view illustrating the operating means for imparting the traversing movement to the blast nozzles, and the means for controlling said operating means and for controlling the admission of the blast to said nozzles. 105

The working chamber A is formed by a drum or casing α provided with a hopper-

shaped bottom a' , and from the head a^2 of said drum extends an exhaust pipe b for carrying off the fine dust evolved by the operation of the sand blast within the chamber. The hopper-shaped bottom part a' of the drum is adapted to contain a suitable quantity of sand for blasting purposes, as shown in Figures 1 and 2. The drum is supported at an elevation suitable for the operator by any suitable means, such as the legs b' . In one side of the drum is an opening b^4 adapted to be closed ordinarily by a door B which may be opened and closed at will for the operator to obtain access to the chamber when desired.

Work-locating devices are positioned within the chamber for the purpose of positioning the work accurately in the path of a sand blast or sand blasts, said work-locating devices being substantially in the horizontal plane of the door B and in the opposite side of the drum a from said door, see Figure 3. One part of the work-locating devices is a bell C , preferably tapering in form and positioned within a suitable opening provided in the drum. At the narrow or reduced end of the tapering bell is a slot c , whereas at the wide mouth of the bell is a marginal flange c' positioned in opposing relation to a side wall of the drum a and adapted to be secured to said drum by bolts c^2 , a gasket c^3 being positioned between the flange of the bell and the drum so as to be compressed by tightening the bolts, and thus secure an air-tight connection between the bell and the drum. Secured fixedly within the bell C is a rest plate D upon which the metal to be treated is placed when it is introduced into the chamber, said rest plate being provided with guides d , as shown in Figures 2 and 3. The guides are secured rigidly to the rest plate and are spaced relatively to each other to receive between said guides the material to be operated upon, said material being represented in the drawings as a piece of flat sheet metal X . The guides embrace the respective side edges of the metal sheet X and they cooperate with the rest plate in locating the material in the path of the blasts.

Another part of the work-locating devices is a stop E , herein shown as a screw positioned opposite to the slot c of the bell, said stop being fixedly supported in position by appropriate means so as to lie in the path of the metal X and thereby arrest the inward movement of said sheet metal X in the operation of introducing the latter into the chamber. The screw E is supported in a transverse member of the bail e , the respective end portions of which are fixed to the bell C at the respective sides thereof, as shown in Figure 3, said screw E being provided with a check nut e' and with a transverse rod e^2 , the latter affording convenient

means for rotating the screw in its bearing in the bail e , so that the material X may be introduced as desired into the chamber. For precluding the escape of sand through the bell in the operation of removing the scale from the surface of the metal sheet X , it is preferred to employ flaps F on the bell C , said flaps being composed of flexible material such as leather or rubber. The flaps are secured by suitable means to the inclined walls of the bell, and thus the flaps occupy a converging relation toward the slot c of the bell, whereby the flaps are adapted to meet at their free edges in order to temporarily close the slot c of the bell and thus preclude the escape of sand through the bell and around the operator. It is apparent, however, that the free edges of the flaps are yieldable upon thrusting the material X in a forward direction, whereby the material is adapted to protrude at its marginal portion through the slot c of the bell in a manner to expose said marginal portion to the sand blasts within the chamber, such inward thrust or movement of the material X being arrested by contact with stop E .

G , H designate the sand blast nozzles, the same being respectively positioned above and below the work-locating devices just described, said nozzles facing toward each other in a manner to direct sand blasts against the respective surfaces of the work X along the marginal portion thereof. The nozzles are movable relatively to the work-locating devices in order to direct the blasts against the material X throughout the width thereof. Means are provided for mounting or supporting the nozzles in movable relation to the material, and it is preferred to employ movement-imparting means which acts to shift the nozzles simultaneously with respect to the work. The nozzles may be mounted in various ways, but it is preferred to pivotally support said nozzles for swinging movement relatively to the material to be operated upon. The upper nozzle G is connected with a pipe g terminating in an elbow g' which is coupled by a union g^2 to a branch pipe g^3 , whereby the nozzle G is pivotally supported by the union g^2 on the branch pipe g^3 . In like manner the nozzle H is carried by a pipe h attached to a sleeve h' and terminating in an elbow h^2 , the latter being connected by a coupling h^3 to a branch pipe h^4 , so that the nozzle H is supported for pivotal movement, the union h^3 being the axis of movement. The pipe g of the nozzle G is provided with a sleeve i to which is connected a sand-feeding pipe I , and into this sleeve i projects a jet nozzle J , the outlet of which is positioned accurately in the centre of the pipe g and sleeve i . The pipe I extends downwardly within the chamber for the lower open end of said pipe to be surrounded by the sand present in the hopper bottom a'

of the drum. The sleeve h' of nozzle H is provided with radial feed openings i' , said sleeve being enveloped or surrounded by the sand within the hopper bottom. Into the 5 sleeve h' extends a jet nozzle J' , as shown in Figure 1, the outlet of which is positioned accurately in the centre of said sleeve h' and pipe h . The branch pipe g^3 extends from the nozzle G to a blast pipe K , whereas the 10 other branch pipe h^4 extends upwardly within the chamber to the blast pipe K , the latter extending through a suitable opening in the drum a , as shown in Figure 1. To this 15 blast pipe K is connected a feed pipe k leading from a reservoir or other source of pressure supply. Said blast pipe K is provided with a suitable valve k' the movable member of which has an arm k^2 to which is attached a link k^3 , the latter extending downwardly to 20 a treadle lever K' , whereby the operator is enabled to open the valve when it becomes necessary to supply the air blast through the pipe K to the jet nozzles $J J'$, the effect of which is to create a sand blast adapted to be 25 delivered by the nozzles $G H$ against the respective surfaces of the material X along the marginal portion thereof.

The means for imparting movement simultaneously to nozzles G, H will now be described, although it is apparent that any equivalent means may be employed. A stuffing box m is attached rigidly to a wall of the drum, through which stuffing box is free to slide a rod L , the inner end of which is provided with a crosshead l , to the ends of which crosshead are pivoted links l' , the other ends of which links are pivoted to the tubes g, h of nozzles $G H$, respectively. The outer end of the reciprocating rod L is pivoted to a slide M , the latter being retained in a fixed guideway m' on an exterior frame M' . This slide is provided with a friction roller n which operates in a groove n' of a rotary cam N , the latter being secured fixedly to a shaft O supported in suitable bearings o on the frame M' . Mounted loosely on the shaft O is a gear P provided with a clutch member p , and with the gear meshes a driving pinion P' on a drive shaft P^2 . A 40 tubular shaft Q is mounted on the shaft O , said tubular shaft being free to slide along the shaft O and being keyed to said shaft O for rotation therewith. The tubular shaft Q is provided with a clutch member q adapted for cooperation with the clutch member p of the driving gear P , but when the shaft Q is moved away from the gear P , its clutch member q is free from engagement with the clutch member p , thus allowing the shaft O 45 to remain stationary, whereas the gear P will be driven by the shaft P^2 . The tubular shaft is provided at one end with a groove q' in which operates the forked end of a 50 shipper lever R , to one end of which is pivoted an operating rod r , the latter being 55 provided at its other end with a hand-grip r' , whereby the rod r and shipper lever R may be operated to impart sliding movement to the tubular shaft Q for the purpose of effecting the engagement of the clutch member q with the clutch member p , so that the gear P will impart rotative movement to the shaft O , the cam N on which shaft operates to impart reciprocating movement to the rod L and thus give the desired traversing movement simultaneously to the nozzles $G H$. When the material is first introduced into the chamber and positioned therein by the work-locating devices, the nozzles $G H$ occupy the initial position at one side edge 60 of the work X , as indicated by dotted lines at the right of Fig. 1, but when the cam N is rotated by the shaft the rod L is moved so as to shift the nozzles with respect to the work in a manner to direct the blasts across a marginal portion of the material X until the nozzles assume the other dotted line position indicated at the left of Figure 1, after which time the cam continues in operation 65 in order to retract the rod L and to return the nozzles $G H$ to their initial positions. On the return of the nozzles $G H$ to their initial positions and the backward movement of the rod L and the slide M , a finger s of the slide acts on a second shipper lever S 70 which is positioned in operative relation to the tubular shaft Q for the purpose of imparting sliding movement to said shaft Q and thus withdraw the clutch member q from the clutch member p , said parts operating as a stop motion to disengage the cam N and arrest the rotation thereof when the nozzles $G H$ shall have completed the traversing movement with respect to the material X . 75

It is thought that the operation and advantages of the invention will be apparent to those skilled in the art from the foregoing description taken in connection with the drawings.

Having thus fully described the invention, what we claim as new, and desire to secure by Letters Patent is:

1. In an apparatus for cleaning metal in sheet form, a substantially closed chamber, a chambered work-locating member extending inwardly with respect to said chamber, said member being provided at its inwardly extending portion with a slot through which is adapted to project a marginal portion of a metal sheet the unexposed surfaces of which are covered by said chambered member, sand-blasting means positioned within said chamber, and adjacent the slotted portion of said chambered member, and means for imparting to the sand-blasting means movement with respect to the chambered work-locating member.

2. In an apparatus for cleaning metal in sheet form, a substantially closed chamber,

4

a chambered work-locating member extending inwardly with respect to said chamber, said member being provided at its inwardly extending portion with a slot through which 5 is adapted to project a marginal portion of a metal sheet the unexposed surfaces of which are covered by said chambered member, a sand-blast nozzle mounted for movement relatively to the slotted portion of said 10 chambered work-locating member, and means for imparting a traversing movement to said nozzle adjacent the slotted portion of said work-locating member.

3. In an apparatus for cleaning metal in 15 sheet form, a substantially closed chamber, a chambered work-locating member extending inwardly with respect to said chamber, said member being provided at its inwardly extending portion with a slot through which 20 is adapted to project a marginal portion of a metal sheet the unexposed surfaces of which are covered by said chambered member, and a plurality of sand-blast nozzles positioned within said chamber and mounted 25 adjacent the slotted portion of said chambered member for directing blasts of sand into contact with the respective surfaces of the metal sheet at the marginal portion thereof exposed within said chamber.

30 4. In an apparatus for cleaning metal in sheet form, a substantially closed chamber, a chambered work-locating member extending inwardly with respect to said chamber, said member being provided at its inwardly 35 extending portion with a slot through which is adapted to project a marginal portion of a metal sheet the unexposed surfaces of which are covered by said chambered member, a plurality of sand-blast nozzles positioned within said chamber and mounted for 40 movement adjacent the slotted portion of said chambered member, means for continuously feeding a blast and sand to said plurality of nozzles, and means for imparting 45 to said nozzles a traversing movement with respect to the slotted portion of said work-locating member.

5. In an apparatus for cleaning metal in 50 sheet form, a substantially closed chamber, a chambered work-locating member extending inwardly with respect to said chamber, said member being provided at its inwardly extending portion with a slot through which 55 is adapted to project a marginal portion of a metal sheet the unexposed surfaces of which are covered by said chambered member, a plurality of sand-blast nozzles positioned within the chamber and mounted on 60 opposite sides of the plane to be occupied by the material, said nozzles being adjacent the slotted portion of said work-locating member and said nozzles facing toward the plane of the slot in said member, and means for imparting to said blast nozzles a traversing 65 movement relatively to the slotted por-

tion of said chambered work-locating member.

6. In an apparatus for cleaning metal in sheet form, a substantially closed chamber, a chambered work-locating member extending inwardly with respect to said chamber, said chambered member being provided at its inwardly extending portion with a slot through which is adapted to pass a marginal portion of a metal sheet the remaining surfaces of which are covered by said chambered member, work-supporting means in cooperative relation to said chambered member, said work-supporting means being positioned for fixedly retaining the material in 70 the plane of said slot of the chambered member, and sand-blasting means within said chamber and adjacent the slotted portion of the chambered member.

7. In an apparatus for cleaning metal in 85 sheet form, a substantially closed chamber, a chambered work-locating member of tapering vertical cross section and provided at its portion of less cross section with a material receiving slot, said chambered member 90 extending inwardly with respect to said chamber, a work-supporting member positioned fixedly within said tapering chambered member and substantially in the plane of the slot therein, and sand-blasting means 95 within said chamber and adjacent the slotted reduced inner portion of said chambered member.

8. In an apparatus for cleaning metal in sheet form, a substantially closed chamber, 100 a chambered work-locating member of tapering cross section and provided in the reduced portion thereof with a material-receiving slot, said chambered member extending inwardly with respect to said chamber, yieldable means for normally closing said slot in the chambered member, and sand-blasting means within said chamber and adjacent the slot of the chambered member.

9. In an apparatus for cleaning metal in 110 sheet form, a substantially closed chamber, a chambered work-locating member extending inwardly with respect to said chamber, said chambered member being provided at its inwardly extending portion with a slot 115 for the passage therethrough of the material to be treated within said chamber, means for normally closing said slot, said slot-closing means being yieldable to the passage of the material to be treated, and sand-blasting means within the chamber and adjacent the slot of said chambered member.

10. In an apparatus for cleaning metal in sheet form, a substantially closed chamber, a chambered work-locating member of tapering cross section and provided at the portion of reduced cross section with a slot for the passage therethrough of the material to be treated, a work-supporting member in fixed relation to said chambered member 125

130

and positioned substantially in the plane of the slot in said chambered member, stopping means adjacent the slot at the inner portion of said chambered member and positioned 5 substantially in the plane of the work-supporting member, and sand-blasting means within said chamber and adjacent the slot of said chambered member.

11. In an apparatus for cleaning metal in sheet form, a substantially closed chamber, a chambered work-locating member extending inwardly with respect to said chamber, said chambered member being provided with a material-receiving slot, a plurality of 15 sand-blast nozzles within said chamber and adjacent the slotted portion of said chambered member, each nozzle being mounted for movement on an axis extending parallel to the axial line of the chambered member, 20 and means for imparting a to-and-fro movement to said blast nozzles relatively to the slotted portion of said chambered member.

12. In an apparatus for sand blasting sheet metal, the combination with a closed 25 chamber, and a blast nozzle positioned therein, of a hollow work locating member extending inwardly with respect to said chamber, said member being open on one side thereof for the free passage therethrough of 30 the material to be operated upon, and said member being provided at its opposite side with an opening of small area through which the material is adapted to pass, and stopping means positioned substantially in 35 alignment with said opening of small area and adjacent said blast nozzle.

13. In an apparatus for sand blasting sheet metal, the combination with a chamber, and a blast nozzle positioned therein, of 40 a hollow tapering work locating member extending inwardly of said chamber, said member being substantially open on one side thereof and provided in its opposite side

with a slot, a work supporting member co-operating with said work locating member 45 and positioned in substantially the plane of the slot therein, and stopping means within the chamber and in cooperative relation to the slot in the work locating member and to 50 said sand blast nozzle.

14. In an apparatus for sand blasting sheet metal, the combination with a chamber, and a blast nozzle positioned therein, of a chambered work-locating member extending inwardly with respect to said chamber, said member being substantially open 55 on one side and provided in its other side with a slot, yieldable closures positioned in contacting relation adjacent the slot in said work locating member and adapted to yield 60 to the pressure of the work during the operation of inserting the latter into the chamber, and stopping means for arresting the insertion of the work so as to expose to the sand blast a margin on the work of definite 65 area.

15. In an apparatus for sand blasting sheet metal, the combination with a closed chamber, a plurality of blast nozzles positioned therein, and means for imparting 70 movement to said blast nozzles, of a hollow work locating member extending inwardly of the chamber and positioned in a plane intermediate the delivery ends of said blast nozzles, said member being provided with 75 a slot for the passage of the material to be operated upon, work-supporting means in operative relation to the work-locating member, and stopping means in operative relation to the work locating member and to said 80 blast nozzles.

In testimony whereof we have hereunto signed our names.

SPENCER C. CARY.
JAMES M. BETTON.
